UNITED STATES PATENT OFFICE.

ARTHUR GOLDBERG, OF NEW YORK, N. Y.

DRUM COVER AND RAIN-PROTECTOR.

1,321,029.

Specification of Letters Patent.

Patented Nov. 4, 1919.

Application filed July 10, 1919. Serial No. 309,806.

To all whom it may concern:

Be it known that I, ARTHUR GOLDBERG, a citizen of the United States, and a resident of the city of New York, borough of the Bronx, in the county of Bronx and State of New York, have invented a new and Improved Drum Cover and Rain-Protector, of which the following is a full, clear, and exact description.

10 This invention relates to musical instruments and has particular reference to covers or protectors for drums.

From my improvement I am able to equip any size drum with a reliable protector of 15 the drum head or heads from rain, snow, or the like, making it possible for the drummer to meet any engagement without regard to the weather, and furthermore which will enable him to manipulate his instrument 20 with impunity and with little or no inconvenience to him and with but a slight, if any, muffling of the music.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had 30 to the accompanying drawings, in which like reference characters designate the same parts in the several views, and in which

Figure 1 is a perspective view of a snare drum indicating the skeleton or frame work of my improvement clamped thereto.

Fig. 2 is a similar view showing the drum cover complete and substantially in playing position.

40 Fig. 3 is a detail sectional view on a plane corresponding to the line 3-3 of Fig. 2.

Fig. 4 is a similar section of the same figure on the line 4-4.

Fig. 5 is a side elevation of a bass drum 45 protector.

Fig. 6 is a similar view showing the protector attached to the bass drum.

Fig. 7 is a diagram indicating approximately the relation of the bass drum to the 50 drummer.

Fig. 8 is a similar view indicating the general appearance of a snare drum in use protected by my improvement.

Fig. 9 is a detail view indicating one of my improved covers or rain protectors detached from the drum and rolled into a compact bundle for storage or carrying upon the drum; and

Fig. 10 is a detail view indicating the means for connecting the rain protector or cover proper detachably to the frame.

Referring now more specifically to the drawings I show in Fig. 1 a plurality of ribs 10 of any suitable practically rigid material such as strap metal, celluloid, hard rubber 65 or the like each having at one end a foot 11 adapted to straddle the rim 12 of the drum and to which the foot is clamped by any suitable means such as a set screw 13 acting through one of the parts of the foot and 70 against one face of the rim, preferably the outer face for convenience. These ribs 10 may be of any suitable number, say from five to eight for a snare drum, or perhaps more for a bass drum and which in operating position project longitudinally of the 75 drum and parallel to one another.

At any suitable points between its end each rib 10 is provided with holes for pivots 14 and 15, said holes being arranged symmetrically in all of the ribs, or at equal distances from the ends.

Extending circumferentially of the protector and from one pivot 14 to the next is a jointed stay 16 comprising two links 16' 85 pivoted together at 17 midway between the connected ribs and pivoted at their remote ends upon pivots 14. The pivot 17 may include a winged nut 18 for gripping the links in extended position in practice and providing for the folding thereof when out of use. The stay members 16 extending entirely around the protector constitute in effect a continuous band or hoop.

Parallel to the band formed by the stay 95 members 16 is another similar band composed of stay members 19 each having two links 19' pivoted adjustably together at 20 with a winged nut, or its equivalent, and having their remote ends pivoted at 15 to the 100 adjacent ribs just above the feet 11 thereof. The several stay members 16 and 19 when extended and tightened serve to make a rigid frame or skeleton for the protector.

For a snare drum a protector for one head 105 is ordinarily sufficient, namely, the head that

is beaten with the sticks. Rain or moisture through other causes ordinarily does not injure the drum head unless said head is beaten while wet. Consequently any moisture that might reach the snare end of the drum is not likely to occasion any injury thereto. When, however, the drum is protected at its upper end as shown in Figs. 2 to 8 the likelihood that rain will reach the 10 snare head is rather remote.

Attached to the skeleton or frame work of the protector is a covering having a head 21 and a cylindrical portion 22. The head is circular and is attached to the end of the 15 cylindrical drum portion preferably by a corded seam 23 just beyond the upper ends of the ribs 10. Any suitable waterproof material may be employed for the cover and the ribs 10 may be secured thereto permanently in any suitable manner, or if desired as indicated in Fig. 10 the drum portion of the cover may be provided with longitudinal pockets into which the ribs 10 are fitted. Except for the frame work already described 20 25 the cover is preferably made of all flexible material whereby the folding thereof along with the folding of the frame incident to the breaking of the joints at 17 and 20 may be readily effected in order to collapse the 30 protector and strap it to the drum or otherwise to the person in idle position during dry weather. In the detail Fig. 10 I show how the ribs 10 may be provided with tapped holes and the screw fasteners 14^a taking the 35 place of the pivots 14 and 15 may serve both to connect the stay links pivotally to each other and also to pass through the outer ply of the covering pocket into the rib. By loosening the screws 14^a the cover may be 40 slipped off of the frame so that the protector from the rain may serve directly as a flexible cover for the drum and so take the place of the usual drum cover which is not a protector for the drum while playing in the rain. 45 On the lower or left end of the cover and protector is arranged a cap 21^a which may be separable from the main drum portion of the cover or preferably carried as a permanent connection as indicated in Figs. 2 and 6. 50 When the drum is being played and the protector is supported as provided for by this device with a space within it for manipulation of the drum sticks or beater a cap 21^a may depend idly on any convenient side of 55 the drum preferably between the drum and the drummer where it would be the least conspicuous. When, however, the cover is slipped over the drum to protect the drum from dust or the like when not in use, the 60 loose portion of the cap at its periphery is adapted to be fastened over the adjacent drum portion of the cover, as by means of buttons or snap fasteners indicated at 21^b.

With reference now more particularly to 65 the snare drum protector I provide for the

upper side of the cover to accommodate the left hand a canopy 24 supported by a frame 25 which in turn is held in extended position by means of one or more brackets 26 clamped by means of set screws or the like 70 27 to the adjacent rim 12. An opening 28 is provided through which the left hand drum stick is projected and manipulated with the hand projecting either through the opening or beneath the canopy. For the 75 right hand an opening 29 is provided around which is a flexible cuff 30 into or through which the right hand may be projected. Thus the cuff portion may project or depend downward with more freedom or 80 flexibility than does the canopy in view of the fact that the right hand naturally occupies a position beneath the protector as a whole. It will be understood from the foregoing description that the drummer may 85 manipulate his drum sticks with practically the same facility as though the protector is not present and yet a shower of rain can have no damaging effect upon the drum. Furthermore since the effect of the snare 90 drum is received largely from the lower or snare end which is unprotected and exposed to the atmosphere, the musical effect with my improvement is not materially different from the ordinary effect. 95

The application of my improvement to a bass drum is similar to that above described. In Fig. 5 I show the protector applied to a drum for the purpose of serving as an ordinary cover when the drum is not in 100 use. The cuff portion 30 may depend on the outside or may be tucked within the drum portion of the cover if preferred. In the case of a bass drum cover the canopy is not employed inasmuch as one hand hole 105 is required and this will be similar to the right hand device above described, into or through which the hand is projected to manipulate the drum beater. If the drummer desires to beat both heads of the drum and with both hands a protector 22' may be provided for each head as indicated in dotted lines in Fig. 7, but otherwise they may be the same. At 31 I show a flexible member 110 in the nature of a two-part strap having a buckle 32 and adapted to be employed either as a handle or carrying device for the drum covered by my improvement in idle condition or it may be used as a means to wrap the protector in a small compact bundle as shown in Fig. 9 when separated from the drum. 115

I claim:

1. The combination with a drum having a rim and a head stretched within the rim and susceptible to damage due to moisture, of a protector for said head comprising a frame, means to clamp the frame to the rim, and a protecting cover carried by the frame in spaced relation to the head giving room 120 125 130

for manipulation of the drum sticks within the protector and serving to protect the drum head from the weather.

2. The herein described drum cover and 5 protector comprising a frame, means to detachably fix the frame to the drum leaving a clear space within the frame adjacent to the head of the drum, and a waterproof covering supported by the frame in spaced 10 relation to said head of the drum whereby the drum may be manipulated while otherwise exposed to the weather, but protected therefrom from damage.

3. The herein described drum cover and 15 rain protector comprising a collapsible frame, means to secure the frame in rigid position to the drum leaving a clear space next to the head within the frame, a rain proof protector carried by the frame in 20 spaced relation to the drum head, said pro-

tector being provided with means to introduce the drum sticks and protect the drum head from dampness.

4. In a drum cover and rain protector, the combination of a series of parallel ribs, 25 means to fix the ribs to the drum, collapsible connections between adjacent ribs, and a flexible rain proof covering carried by the frame in spaced relation to the drum head and giving access for the drummer to the 30 space within the protector for the introduction and manipulation of the drum sticks.

5. The herein described drum cover and 35 protector comprising a collapsible frame, a two-part strap connected thereto and including a buckle, said strap serving as a handle in one position of the protector and as a binding member for the protector in another position thereof.

ARTHUR GOLDBERG.
